The ornamental design for a drifting kart, as shown and described.

DESCRIPTION

FIG. 1 is a perspective view of a drifting kart which embodies my design.

FIG. 2 is a different perspective view of the drifting kart of FIG. 1.

FIG. 3 is a top view of the drifting kart of FIG. 1.

FIG. 4 is a left side view of the drifting kart of FIG. 1.

FIG. 5 is a right side view of the drifting kart of FIG. 1.

FIG. 6 is a front view of the drifting kart of FIG. 1; and, FIG. 7 is a rear view of the drifting kart of FIG. 1.

Broken lines are used to illustrate features of the drifting kart which form no part of the claimed design.

The evenly broken lines are used to illustrate portions of the drifting kart that form no part of the claimed design.
